UNITED STATES PATENT OFFICE.

CHARLES OSEAN, OF WOODCLIFF, NEW JERSEY, ASSIGNOR TO NATIONAL CARBON COMPANY, INC., A CORPORATION OF NEW YORK.

FLASH LIGHT.

Application filed March 23, 1922. Serial No. 546,090.

This invention relates to flashlights and particularly to an improved end cap and spare lamp holder therefor.

When the lamp in the lighting circuit of a 5 flashlight is burned out or otherwise rendered inoperative, it is advantageous to have a spare lamp immediately available, and to insure this it is desirable that the spare lamp be carried along with the flashlight so that 10 a new lamp may be quickly substituted for the defective one. In focusing flashlights it is moreover desirable to have an end cap provided with rigid means for engaging the bottom end of the battery to adjust the lamp 15 with respect to the reflector to vary the spread of the light rays from the lamp.

Accordingly, the primary objects of the invention are to provide an improved end cap and spare lamp holder arranged to 20 house one or more spare lamps and which shall not materially increase the size of the flashlight casing with which it is used. A further object of the invention is to provide 25 an end cap and spare lamp holder especially adapted for use with focusing flashlights, whereby the focus of the operative lamp may be readily adjusted and whereby access may be had to the spare lamp compartment without disturbing the focal adjustment of the 30 flashlight.

The above and other desirable objects are attained by the present type of end cap and spare lamp holder which, generally speaking, comprises a tubular body threaded at 35 one end whereby it may be adjustably coupled to the rear end of the flashlight casing, and to the open end of which a conductive cup-shaped spare lamp holding shell is secured. The bottom of the spare lamp holding shell is disposed so as to engage the 40 bottom end of the flashlight battery to adjust it axially in the casing as the tubular body is screwed onto the casing. The open end of the cup-shaped shell faces rearwardly so that 45 access may be had to the interior thereof without unscrewing said body from the casing. The lamps may be loosely disposed in the shell, but to prevent rattling and breakage thereof it is desirable that the lamp or 50 lamps be securely held, as by fingers punched from the body of the shell or formed separately and secured therein. The open end of the shell may be closed by a cover, desirably one that is removably attached to the 55 shell or to the tubular body. The tubular

body and the lamp holding shell are removable from the casing as a unit when it is desired to renew the battery or inspect the inside of the casing.

The above and other objects and the novel 60 features of this invention will be apparent from the following description taken in connection with the drawings in which Figure 1 is a longitudinal sectional view of a flashlight embodying this invention, parts being 65 shown in elevation; Figure 2 is an enlarged central sectional view of a combined end cap and spare lamp holder illustrated in Figure 1; and Figures 3, 4 and 5 are central sectional views of other combined end cap and 70 lamp holders embodying this invention.

While the invention is illustrated as applied to a focusing flashlight of a desirable construction it will be understood that it may be advantageously applied to other 75 types of focusing flashlights as well as those of the non-focusing type. In Figures 1 and 2 of the drawings a flashlight casing C of metal, fibre or other suitable material has a flaring front end F that contains a reflector 80 R and a cover glass or lens L. The reflector R and a miniature incandescent lamp A are mounted for relative adjustment axially of the reflector to vary the position of the filament of the lamp with respect to the focus 85 of the reflector and thereby change the spread of the light rays from the lamp. Such relative adjustment may be accomplished in any suitable manner, the arrangement disclosed being more fully set forth in 90 the application of Lee J. Voorhees, Serial No. 466,639, filed May 4, 1921. Briefly, this arrangement comprises a lamp holder or socket 10 that is slidable in a central aperture in the reflector, a helical spring 11 having one end bearing against the reflector and its other end bearing against an enclosing member 12 secured to the holder 10 and retaining the latter with the lamp carried by it at the inner limit of its adjustment. The 100 spring 11 also maintains a conductive part of the holder always in contact with the central carbon contact of the battery B within the casing. When the battery is moved against the pressure of the spring 11, the 105 socket 10 and the lamp A move therewith along the axis of the reflector, changing the position of the lamp filament with respect to the focus of the reflector and varying the 110 spread of the rays from the lamp. The com-

pressed spring 11 is adapted to move the lamp and battery in the reverse direction, as will be apparent.

The improved means for effecting the adjustment of the battery B and the lamp A in circuit with it comprises an end cap and spare lamp holder that is adjustably and detachably coupled to the bottom end of the casing C. The lamp holder is desirably a receptacle in the end cap body, which receptacle may of course carry other spare parts. The end cap member comprises a tubular metal body that is provided with means such as threads for coupling it to a corresponding portion at the rear end of the casing C. The rear wall of the end cap is in part at least made up of a receptacle that carries the spare bulb or spare parts. This receptacle is desirably in the form of a cup-shaped metal shell that is secured in the tubular body in contact therewith and has its bottom disposed so as to rigidly bear against the bottom of the battery in the casing when the end cap body is coupled thereto. Accordingly, when the end cap body is adjusted along the casing the lamp A will be moved inwardly or outwardly along the axis of the reflector. The cup-shaped spare lamp holding shell being desirably of conductive material, also is a negative contact for the battery and forms a part of the electrical circuit including the end cap, the battery B and the lamp A, which circuit is controlled by the switch S, in the usual manner.

As illustrated in Figures 1 and 2, one desirable form of spare lamp holder and end cap comprises a suitable tubular metal body 20 having threads 21 at its open end whereby the same may be adjustably coupled to the usual threads 22 at the rear end of the casing C. The other end of the tubular body 20 has an inturned flange 23 leaving an aperture to accommodate the cup-shaped spare lamp holding shell 24 that has its open end secured to the flange 23, as by means of the interlocking seam 25. The lamp holder shell 24 is desirably of metal so as to form a conducting member between the tubular body 20 and the battery B against which the bottom wall 27 of the shell is arranged to bear. The wall 27 may have an outward projection 28 to engage the bottom end of the battery. The shell 24 forms a receptacle to contain spare parts, such as one or more spare lamps. These lamps may be loosely contained in the shell 24, but to avoid rattling and breakage they are desirably either held in place by packing, such as paper or cotton, or they may be rigidly supported by fingers which are either punched from the body of the shell 24 and bent into the same or formed separately and secured into the shell. In the form shown in Figures 1 and 2, the lamps may be carried

by U-shaped clips 30 secured to the inner side of the bottom wall 27 as by rivets 31, the limbs of the clips 30 being spring fingers which support the spare lamps with their axes in the same plane and parallel to the bottom wall 27 but with the bulb and base of one lamp opposite the base and bulb of the other lamp.

The open end of the shell 24 faces rearwardly and may be closed by a suitable cover. As illustrated, a cover 32 may have a flange 33 that fits into the mouth of the shell 24 and may be secured in place by suitable means, as by threads 331 which fit the threaded portion 231 of the shell. The outer surfaces of the tubular body 20 and the cover 32 may be knurled to facilitate manipulating them.

In operation, when the body 20 is secured onto the casing C, the shell 24 acts as a follower, the bottom projection 28 thereof engaging the bottom end of the battery B and moving the same as well as the lamp holder 10 and the lamp A along the axis of the reflector to vary the spread of the rays as desired. When the body 20 is turned in the reverse direction, that is, to unscrew it, the compressed spring 11 acts to move the lamp holder with the lamp and battery in the opposite direction, as the body 20 and the shell 24 are retracted, restoring the lamp to its original position with respect to the reflector focus. At any of its adjusted positions the tubular body 20 will retain the lamp A at a desired focus, and a lamp may be withdrawn from the lamp holding shell 24 and substituted for the lamp A without disturbing the focal adjustment.

While Figures 1 and 2 illustrate an advantageous type of end cap and spare lamp holder and a combination of the same with a focusing flashlight, it will be understood that the details of the construction of the combined end cap and lamp holder may be varied without departing from the principles of the invention or sacrificing any of its advantages, and the end cap and spare lamp holder may be advantageously embodied in a non-focusing flashlight. For example, in Figure 3 the lamp holding shell 242 may have its lip or outer end 242' secured in a groove 202' by the inwardly curled flange 202'', and the cover member 322 may be detachably connected to the device by a bayonet slot 322' in the cover that engages the pin 322'' within the shell 242. Otherwise the combined end cap and spare lamp holder shown in Figure 3 is substantially the same as the one shown in Figures 1 and 2.

Another type of combined end cap and spare lamp holder is illustrated in Figure 4 in which the tubular body 203 is provided at one end with threads 35 whereby the body may be adjustably and detachably coupled

to the threaded part 22 of the casing C. At its opposite end the body 203 has threaded portion 36 that is adapted to fit the threaded part 37 of the end cap 38 that usually is fitted to the casing C, which thus serves as a cover for the shell 243. The body 203 has an interior groove 203' that is arranged to receive and retain the edge 243' of the cup-shaped lamp holding shell 243. The lamp holding members carried by the shell 243 are formed integral therewith by stamping out tongues 39 with apertures 40 therein of a size to have the bases of the spare lamps screwed into the same.

15 The improved end cap and lamp holder illustrated in Figure 5 comprises a tubular body 204 that has threads 42 whereby it may be coupled to a flashlight casing and threads 43 whereby the usual end cap 38 of the casing may be coupled thereto to close the shell 244, as in the arrangement shown in Figure 4. The spare lamp holding shell 244 is secured in the body 204 in a different manner, however, an inwardly extending 25 flange 204' having its edge united to the lip or outer edge of the lamp holder shell by an interlocking seam 25', as in the form shown in Figures 1 and 2. The lamp holding tongues 39' are similar to those shown in Figure 4.

30 The invention is not limited to the exact details of construction illustrated and described, as various changes may obviously be made therein.

35 I claim:

1. A closure for a flashlight casing comprising a tubular body having means for detachably coupling it to such casing, a spare lamp receptacle secured in said body and adapted to bear against a battery in said 40 casing, and a removable cover for said receptacle.

45 2. A combined end cap and spare part holder for flashlights comprising, the combination of, a threaded tubular body adapted to be coupled to a flashlight casing, a cup-shaped spare part holding shell carried by said body and having its open end facing rearwardly, the bottom of said shell being 50 arranged to bear against a battery in said casing, and a removable cover closing the open end of said shell.

55 3. The combination with a body having means for coupling it to a flashlight casing, of a conductive cup-shaped shell secured therein to provide a compartment within said body and having its bottom end arranged to continuously engage the bottom of a battery in said casing to support such 60 battery.

65 4. A combined end cap and spare lamp holder for flashlights comprising the combination of a tubular body threaded at one end for coupling it to a flashlight casing, a cup-shaped spare-lamp holding shell hav-

ing its open end united to the other end of said body and means at its bottom end arranged to bear against a battery in said casing, and a cover closing the open end of said shell.

70

5. A combined end cap and spare lamp holder for flashlights comprising the combination of a threaded tubular body adapted to be coupled to a flashlight casing, a conductive cup-shaped spare lamp holding shell 75 carried thereby and having its bottom end arranged to engage the bottom of a battery in said casing, and a removable cover closing the other end of said shell.

6. A combined end cap and spare lamp 80 holder for flashlights comprising the combination with a cup-shaped spare lamp holding shell carrying lamp supporting means, of a tubular body having means adjacent one end thereof for coupling the same to a 85 flashlight casing and having means securing the open end of said shell thereto, and a cover for closing the open end of said shell.

7. A combined end cap and spare lamp 90 holder for flashlights comprising the combination of a threaded tubular body adapted to be coupled to a flashlight casing, and a cup-shaped shell therein carrying spare lamp supporting means.

8. A combined end cap and spare lamp 95 holder for flashlights comprising the combination of a threaded tubular body adapted to be coupled to a flashlight casing, and a cup-shaped shell therein comprising spare lamp holding means and having means at 100 one end adapted to bear against the bottom of a battery in said casing.

9. A flashlight comprising the combination of an incandescent lamp, a battery in circuit with said lamp, a casing containing 105 said battery, a conductive cup-shaped shell having its bottom end bearing against the bottom of said battery, and a shell-supporting member detachably coupled to said casing and having a grooved part cooperating 110 with the edge at the open end of said shell to retain the latter in said member.

10. A flashlight comprising, in combination, an incandescent lamp, a battery in circuit with said lamp, a casing therefor, a cup-shaped shell having its bottom bearing against the bottom of said battery, a cover for said shell, and means for enclosing said shell and coupling it to said casing.

11. A flashlight comprising a miniature 120 incandescent lamp, a reflector, means whereby said lamp and said reflector are relatively movable to permit the adjustment of said lamp with respect to the focus of said reflector, a battery in circuit with said lamp, a casing therefor, a conductive cup-shaped shell having its bottom bearing against the bottom of said battery, and a tubular body carrying said shell and comprising means 125 for adjustably coupling it to said casing.

130

12. A flashlight comprising a miniature incandescent lamp, a reflector, means whereby said lamp and reflector are relatively adjustable, a battery in circuit with said lamp, 5 a casing for said battery, an adjustable conductive cup-shaped shell comprising lamp holding means and having a bottom part engaging the bottom of said battery, and a cover for said shell.
- 10 13. A flashlight comprising an incandescent lamp, a reflector, means whereby said lamp is mounted for movement axially of said reflector, a battery in circuit with said lamp and movable therewith, a casing for 15 said battery, and a combined end cap and spare lamp holder comprising a threaded tubular body adjustably coupled to said casing, a conductive cup-shaped shell secured to said body, said shell carrying lamp holding 20 means and having a bottom part engaging the bottom of said battery, and a cover closing said shell.
14. The combination of a tubular body having means adjacent one end whereby it 25 may be detachably coupled to a flashlight casing, and conductive means in said body for engaging against a cell to hold it in place in said casing and constructed to carry a spare lamp for a flashlight.
- 30 15. The combination of a tubular body having means adjacent one end whereby it may be detachably coupled to a flashlight casing, and a rigid conductive metal shell in said body providing a compartment to contain a spare bulb and arranged to engage 35 against the bottom of a battery cell in said casing to hold such cell in place in said casing and to form a part of the circuit including said cell.
16. The combination of a cap closed at one end and threaded adjacent its opposite end whereby it may be detachably coupled to a flashlight casing, said cap having an interior groove, and spare lamp carrying means in said cap having a part engaging in said groove to secure said means in place and a part arranged to bear against the bottom of a cell in said casing and to form a portion of a circuit including said cell. 45
17. The combination of a cap closed at one end and threaded adjacent its opposite end whereby it may be detachably coupled to a flashlight casing, said cap having an interior groove, and a metal shell within said cap having a portion engaging in said groove 55 and a portion spaced from the threaded part of said cap and arranged to engage the bottom of a cell to hold it in place in said casing and to form a part of the circuit including said cell, said shell being constructed to carry 60 a spare lamp for a flashlight.
18. A flashlight comprising the combination of an incandescent lamp, a battery for lighting said lamp, a casing for said battery, spare lamp holding means bearing 65 against said battery, and an end cap coupled to said casing and carrying said lamp holding means.
19. A flashlight comprising the combination of an incandescent lamp, a battery in 70 circuit with said lamp, a casing for said battery, an end cap detachably coupled to said casing, and a rigid conductive shell secured within said end cap and engaging the bottom of said battery said shell forming a compartment inside said cap. 75

In testimony whereof, I affix my signature.
CHARLES OSEAN.
